UNITED STATES PATENT OFFICE.

MICHAEL E. POWERS, OF BALTIMORE, MARYLAND.

LOCK.

Application filed December 8, 1921. Serial No. 520,229.

To all whom it may concern:

Be it known that I, MICHAEL E. POWERS, a citizen of the United States, residing at Baltimore, in the State of Maryland, have 5 invented certain new and useful Improvements in Locks, of which the following is a specification.

This invention relates to improvements in locks and has for its object to provide a 10 simple, cheap and efficient lock and hasp combined, and to provide a temporary locking means.

The invention consists of the novel construction and arrangement of the parts and 15 combination of parts hereinafter more fully set forth in the following specification and pointed out in detail in the claim:

In the accompanying drawing,—

Figure 1 is a top plan view showing the 20 temporary locking device in the unlocked position.

Figure 2 is a similar view to Figure 1 but showing the temporary locking device in the locked position.

25 Figure 3 is a side elevation of Figure 1.

Figure 4 is an inverted plan view with the back of the case removed and showing the parts in the unlocked position.

30 Figure 5 is a detail plan view of the temporary locking device.

Referring to the accompanying drawings, forming part of this specification, and in which like reference numerals designate like parts throughout the several views 35 thereof, 1 designates the case having a hinged hasp 2 adapted to be secured in any desired position so that the lock can be brought down over the eye or staple 3. The said staple 3 is secured in position by screws 40 and projects through the central opening 4 of the lock. On the upper surface of the

lock case is a temporary locking device 5 having two points 6 adapted to be turned to project through the eye or staple 3, as shown in Figure 2, in which position the 45 end 7 of the temporary locking device covers the key-hole 8. The said temporary locking device 5 is revoluble under the lugs 9 on the upper surface of the case 1. Within the case 1 is a locking bolt 10 on the end 50 of the lever 11 which latter is pivoted at 12 and is operated by the bar 13 pivoted to the lever 11 at 14. The key 15 operates against the tumblers 16 and bar 13 to throw the lever 11 and the locking bar 10. Within the 55 case 1 is a metal spring 17 secured at one end to the case 1 and having a push button 18 on its free end. When said spring 17 is pushed in against the tumblers 16 and bar 13, the locking bar 10 will be thrown from 60 the unlocked to the locked position, thus dispensing with the use of the key to lock the device.

The staple 3 is first secured in position, and the hasp 2 is then secured in position so 65 that the lock can be brought down over the staple, with the latter projecting through the central opening 4, in which position the locking bar 10 is moved, by key or by the push button 18, to the locked position.

Having thus described my invention, what 70 I claim is:

A lock comprising a casing having an opening therethrough, a staple adapted to project through said opening, a locking bar 75 pivoted within said casing and adapted to project through said staple, a key-bar pivoted to said locking bar, and a key adapted to co-operate with said locking bar.

In testimony whereof I affix my signature. 80

MICHAEL E. POWERS.
